UNITED STATES PATENT OFFICE.

HENRY WILLIAM RICE, OF PRAHRAN, MELBOURNE, VICTORIA, AND LESLIE A. STURROCK, OF ROYAL PARK, MELBOURNE, VICTORIA, AUSTRALIA.

WIRE-BOUND BOX AND THE LIKE.

1,317,817.

Specification of Letters Patent. Patented Sept. 30, 1919.

Application filed April 13, 1916. Serial No. 90,884.

To all whom it may concern:

Be it known that we, HENRY WILLIAM RICE, a subject of the King of Great Britain and Ireland, residing in the postal district 5 of East Prahran, a division of the city of Prahran, a suburb of the city of Melbourne, in the county of Bourke, State of Victoria, Commonwealth of Australia, and whose post-office address is 36 Chomley street, in 10 the said postal district of East Prahran, and LESLIE ALEXANDER STURROCK, a subject of the King of Great Britain and Ireland, residing in the postal district of Royal Park, a suburb of the city of Melbourne, in the 15 county of Bourke, State of Victoria, Commonwealth of Australia, and whose post-office address is 511 Royal Parade, in the said postal district of Royal Park, have invented certain new and useful Improvements in and 20 Connected with Wire-Bound Boxes and the like, of which the following is a specification.

This invention relates to wire bound boxes, crates, cases and the like and particularly 25 to the type wherein four sides, each carrying two opposite end cleats, are united by binding wires to permit of the said sides being wrapped or folded around two ends to form a complete box.

The chief object of the present invention 30 is to provide a box or the like of the wire bound type which can be readily opened when testing of its contents is necessary, which is strong and durable and which may 35 be produced at a greatly reduced cost owing to the saving effect in material and labor. The essential features of the invention are the provision of novel slots and retention wires to hold the box sides in position or in 40 correct relationship while the box is being assembled and when the box is open.

The invention is equally applicable to wire bound boxes and to some classes of crates and cases having binding wires or the 45 like.

Referring to the accompanying drawings, which are to be taken as part of this specification:

Figure 1 is a perspective view of a box according to the invention the lid of the box

being open and part thereof being broken away, and a part of one end thereof being also broken away.

Fig. 2, is a detail inside perspective view showing a grooved end cleat. 55

Fig. 3, is a detail sectional view showing the application of a retention wire.

Fig. 4, is a detail perspective view showing the side slotted for use in conjunction with a grooved cleat. 60

Fig. 5, is a view of a retention wire, the dotted lines indicating the bending of the end of the wire after its application to a box.

Fig. 6, is a view of a modified retention wire, the dotted lines indicating the bending of the end of the wire after its application to a box. 65

Fig. 7, is a detail showing a modification.

The invention is applied to a box having a first side 2, a second side or bottom 3, a 70 third side 4, and a fourth side or top 5, the sides being formed of suitable thin material.

With the foregoing are used two end sheets 14 which may be plain. Attached to each side are two end cleats 6 each having 75 its ends beveled as at 7.

The sides 2, 3, 4 and 5 are united by binding wires 8 which may be secured to the sides by staples 9, which also secure the end cleats 6 to the sides as usual. Each end of 80 each binding wire projects beyond the meeting edges of the box sides forming wire extensions 12 as usual.

The features so far described are all well known. 85

The opposite cleats 6 attached to the opposed sides 2 and 4 are respectively provided with wire holes 13 and vertically disposed slots 18. The holes 13 being near the upper ends of the cleats as shown in Fig. 1 and 90 the slots 18 extending vertically into the upper ends of the opposed cleats as shown.

To retain the sides in correct relationship while the box is being packed retaining wires 15 are employed. Each wire is of a 95 predetermined length and one end thereof is preferably bent sidewardly as at 16. In practice a pair of retaining wires each having a side bend 16 is passed through the holes 13 formed in the upper ends of the 100

cleats 6 attached to the side 2 then the other bent end of the wire is engaged with the slot 18 as indicated in Figs. 1 and 3, the bent end or head of the wire being inserted between the slotted end of the cleat 6 and the adjacent end of the box, as more clearly shown in Fig. 3, securely holding the sides together and the box in shape. The box sides 2 and 4 are pressed toward each other while the retaining wires are being engaged with slots 18. After the retaining wires have been placed in position the said box sides cannot move apart and are correctly positioned. The ends 14 of the box can then be pressed tightly into position and owing to the cleats 6 and retaining wires 15 are held securely between the box sides. The lid 5 can be closed after the box has been packed. The extensions 12 of the binding wires may then be twisted together in the usual manner to seal the box.

The retaining wire may have a head 19 at one end (see Fig. 6) and a metallic washer 20 bearing against said head. The head and washer 20 of each retaining wire may be inserted between the slotted end of the cleat 6 and side 4 which are slightly sprung apart to permit the introduction of the said head and washer (see Fig. 3), the wire passing through the corresponding groove 18. The other ends of the wires pass through the holes 13 in the cleats and in the first side 2 as shown in Fig. 3. This construction provides for readily freeing the side 4, if desired, after opening the lid 5 of the box.

If desired grooves 18 may be formed in the upper ends of the opposed cleats on both sides 2 and 4 of the box, (see Fig. 7) and corresponding grooves 22 may be formed in the said sides adjacent said grooves 18, and the retaining wires may have a head 19 and washer 20 at one end; and a head 23 and washer 24 on its other end. It will be obvious that when the first and third sides require retaining it is only necessary to insert the ends of the proper retaining wires into the grooves 18 and 22 and the sides of the box will be prevented from spreading.

I claim:

1. In a wire bound box the combination of cleats having open vertically disposed slots or grooves of the character described in their upper ends, the bottom of said slots being horizontal or at right angles to the plane of the box sides; and retention wires extending horizontally between the sides of the box, each of said retention wires having one end passing completely through a cleat and the adjacent side of the box and the other end passing through the said slot in an opposed cleat and detachably engaged with such cleat, for the purpose set forth.

2. In a wire bound box the combination

of cleats having open vertically disposed slots or grooves of the character described in their upper ends the bottom of said slots being horizontal or at right angles to the plane of the box side; and retention wires extending horizontally between the sides of the box, each of said retention wires having one end passing completely through a cleat and one side of the box and turned over to engage the exterior binding wire and the other end of such retention wire passing through the said slot in an opposed cleat and having its headed end detachably engaged with the outer side of such cleat and between the cleat and box side, substantially as and for the purpose set forth.

3. In a wire bound box having top, bottom, ends and sides; cleats attached to the sides having open ended vertically disposed slots or grooves in their upper ends, retention wires extending horizontally across the ends between cleats on opposite sides of the box, each of said retention wires having one end passing through a cleat at one side of the box and through the adjacent side of the box and having its outer end engaged with the exterior of such side of the box; the other end of the said retention wire passing through the slotted end of opposed cleat on the opposite side of the box and detachably engaged with such cleat, substantially as and for the purpose set forth.

4. In a wire bound box having top, bottom, ends and sides, and exterior binding wires; cleats attached to the sides of the box, and having open vertically disposed slots or grooves in their upper ends and retention wires extending horizontally and transversely across the ends of the box and between the sides of the box, each of said retention wires having one end passing completely through a cleat and one side of the box and the other end of such retention wire passing through the said slot in an opposed cleat on the opposite side of the box and having a head on its end engaging the outer side of such cleat between the cleat and box side, substantially as and for the purpose set forth.

5. In a wire bound box having top, bottom, ends and sides, and exterior binding wires; opposite cleats attached to opposite sides of the box, and having open vertically disposed slots or grooves in their upper ends, the bottom of said slots being horizontal or at right angles to the plane of the box sides; and retention wires extending horizontally and transversely across the ends of the box and between the sides of the box, each of said retention wires having one end passing completely through a cleat and one side of the box and having its outer end turned over to engage the exterior binding wire; and the other end of such retention

wire passing through the said slot in an opposed cleat on the opposite side of the box and having a head on its end engaging the outer side of such cleat between the cleat and box side, substantially as and for the purpose set forth.

In testimony whereof we affix our signatures.

HENRY WILLIAM RICE.
L. A. STURROCK.
